UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

DEVICE FOR PRODUCING SLITS, GROOVES, OR THE LIKE IN THE SURFACE OF MONOLITHIC STRUCTURES

Application filed November 29, 1926. Serial No. 151,415.

My present invention relates in general to laying concrete or the like monolithic structures, and has particular reference to a device for producing a slot or slit, or even a groove, in the surface of such structures, primarily for the purpose of developing a line of weakness so as to control cracks in the structure due to expansion and contraction.

For the purpose of illustrating the salient features of the invention I have selected that form of the device peculiarly adaptable for use in producing these slits or slots in the surface of paving structures, such for instance, as concrete streets or highways, or paving in general.

In the accompanying drawing, in which the form of the invention above mentioned is illustrated, Figure 1 is a perspective view of one form of the device.

Figure 2 is a perspective view of a slightly modified form.

Figure 3 is a perspective view of still another form.

Figure 4 is a view in side elevation illustrating the use of the invention; and

Figure 5 is a section thru a concrete paving, showing the results accomplished by the use of the invention.

Referring now to the drawing in detail and calling particular attention to Figure 5, A represents a concrete highway, street or pavement, and it is a more or less common practice to equip such a structure with either paving joints to compensate for expansion and contraction, or else to produce slots or slits in the surface thereof which extend a limited distance in the depth of the concrete and provide a line of weakness both transversely and longitudinally of the concrete, so that upon expansion of the concrete any crack resulting from such condition will follow the line of the slot or slit, for instance as illustrated as at B.

I have devised a very simple, practical device for producing these slots or slits, as shown at B in Figure 5. Accordingly, one form of the invention consists in mounting a block or other like device 5 upon the edge 6 of a sheet metal strip or the like 7.

With such a device I can very conveniently

produce these slots or slits by laying the device along the area where a slit should be provided, and then imposing pressure upon the block 5 so as to press the strip 7 into the concrete. It, of course, is understood that this operation is performed while the concrete is in a penetrable, plastic condition, in other words, before it has set. It mustn't be too soft, however, because when the device is removed the concrete must be at least firm enough to leave the impression on the strip 7 so as to make a slit, for instance as shown at B in Figure 5.

Since the strip 7 is centered in the block 5, i. e. to say, mounted intermediate longitudinal edges, the under surface of the block on opposite sides of the strip will offer relatively broad contacting areas for the surface of the concrete, so as to limit the penetration of the strip 7, and the area of the block will evenly distribute the pressure necessary to imbed the strip 7, so that the block is not apt to be imbedded in the concrete even though the concrete happened to be comparatively soft. This principle will be readily appreciated upon reference to Figure 4.

Practically the same arrangement is illustrated in Figure 2, except that the attached edge of the strip 7 is made with an enlargement 6^a, so that the strip becomes practically permanently anchored to the block 5, and there is no danger of the same pulling away from the block. The strip 7 for all practical purposes is in reality a blade, since, while it doesn't necessarily require a slicing or cutting action to properly operate, such an action may be used in special instances by forming the strip 7 as a long triangle, and as such it may be drawn thru the concrete to make the slit. This does not mean that the other forms of the device cannot be drawn thru the concrete, but by cutting the blade on the slant a more pronounced cutting or slicing effect is realized, which would be more desirable in pulling the device thru the concrete, as compared to just laying it upon the surface of the concrete and forcing the blade in.

I claim:

1. In a device of the class described, a triangular, blade-like strip adapted to be im-

bedded in a concrete or the like structure for producing a slit therein, and an integral block-like head for manipulating the triangular, strip-like blade, and in which one edge of the triangular, strip-like blade is imbedded, the strip being imbedded in the underside of the block-like head intermediate the longitudinal edges thereof so as to leave a relatively wide surface on the under-
10 side of the block for limiting the penetration of the triangular, strip-like blade substantially as/and for the purpose described.

2. In a device of the class described, a blade adapted to be imbedded in a concrete structure for producing a slit therein, and a single piece blade manipulating block, said blade having one edge thereof insertably mounted within the block and positioned centrally with respect thereto, and having a work en-
15 gaging edge which is angularly disposed with respect to the side of the block to which said blade is secured, the angular arrangement of the work engaging edge rendering the device longitudinally movable to form a slit in the concrete structure.

3. In a device for marking joints in concrete paving, a blade having an enlarged head along one edge, and a blade holding block having a longitudinal recess in which the enlarged head of the blade is adapted to be inserted.

4. In a device for marking joints in concrete paving, a blade having one edge retro-
20verted to form a bead, and a blade holding block having a longitudinal recess in which the beaded edge of the blade is adapted to be inserted.

Signed at Chicago, Illinois, this 24 day of November 1926.

40 ALBERT C. FISCHER.
